UNITED STATES PATENT OFFICE

123,819

DESIGN FOR A COMBINED CONTAINER AND DISPLAY FOR GOLF TEES OR THE LIKE

George H. Perryman, Teaneck, N. J.

Application September 17, 1940, Serial No. 95,135

Term of patent 14 years

To all whom it may concern:

Be it known that I, George H. Perryman, a citizen of the United States, and a resident of the town of Teaneck, county of Bergen, and State of New Jersey, have invented a new, original, and ornamental Design for a Combined Container and Display for Golf Tees or the like, of which the following is a specification, reference being had to the accompanying drawing, forming a part thereof, in which:

Fig. 1 is a front elevational view of the combined container and display, for golf tees or the like, showing my new design; Fig. 2 is a top plan view; and Fig. 3 is an end elevational view thereof.

I claim:

The ornamental design for a combined container and display for golf tees or the like, substantially as shown.

GEORGE H. PERRYMAN.
